(57) **CLAIM**

The ornamental design for a dual chamber package, as shown and described.

DESCRIPTION

FIG. 1 is a bottom perspective view of a dual chamber package shown in a first configuration, with the dual chambers “capped” and attached to one another;

FIG. 2 is a front elevation view thereof;

FIG. 3 is a rear elevation view thereof;

FIG. 4 is a right-side elevation view thereof;

FIG. 5 is a left side elevation view thereof;

FIG. 6 is a top plan view thereof;

FIG. 7 is a bottom plan view thereof;

FIG. 8 is a vertical cross-section view thereof, taken along and in the direction of line 8-8 in FIG. 4;

FIG. 9 is a top perspective view of the dual chamber package of FIG. 1 shown in a second configuration, with the dual chambers “uncapped” and detached from one another, shown with environmental subject matter;

FIG. 10 is a top perspective view of the dual chamber package of FIG. 1 shown in a third configuration, with the dual chambers “capped” and detached from one another;

FIG. 11 is a front elevation view thereof;

FIG. 12 is a rear elevation view thereof;

FIG. 13 is a right-side elevation view thereof;

FIG. 14 is a left-side elevation view thereof;

FIG. 15 is a top plan view thereof; and,

FIG. 16 is a bottom plan view thereof.

Broken lines in the drawings represent environmental subject matter, and form no part of the claim.

1 Claim, 15 Drawing Sheets
